DENTAL CASTING APPARATUS

Application filed May 6, 1929. Serial No. 360,636.

My invention relates to a new and improved method of and mechanism for making castings, and more particularly, dental castings of the larger type such as bridge work and the like.

One of the objects of my invention is to provide a method of making dental castings by the "lost-wax" method whereby hot air under suitable pressure will be utilized 10 for forcing the molten metal into the cavity of the mold. Instead of using a wax pattern for making the casting, I may use a hollow pyroxylin pattern whose outer wall has been formed into the desired shape by means of 15 wax. This pyroxylin pattern can be removed by heating the mold and it has the advantage of leaving a cavity in the investing material which has a smooth and dense wall.

Another object of my invention is to provide a method whereby small castings, such as 20 dental castings, can be quickly and uniformly made in a dense and homogeneous form, and to also make it possible to make castings of metals having high melting points such as 25 palladium, platinum, nickel and high melting alloys.

Another object of my invention is to permit the use of rarefied hot air, or a rarefied hot gas for molding under pressure, the said 30 hot air or hot gas having a pressure which is less than the normal pressure corresponding to the temperature of the air or gas utilized. While I do not wish to limit myself to the gas which may be utilized, I prefer to use an 35 inert gas such as nitrogen or carbondioxide.

Another object of my invention is to provide a simple device in which the heating of the hot air or gas utilized permits the operator to determine the temperature and pressure 40 of the gas which is being utilized, without making it necessary to add an expensive pyrometer to the apparatus.

Other objects of my invention will be set forth in the following description and drawings, which illustrate a preferred embodiment 45 of my invention, it being understood that the above general statement of the objects of my invention is intended to generally explain the same and not to limit it in any manner.

Fig. 1 is a vertical sectional view, partially in elevation, of a mechanism which may be utilized to carry out my method.

Fig. 2 is a sectional view on the line 2—2 of Fig. 1.

Fig. 3 is a detail view of the molding flask.

The casting of inlays made of gold or other precious metals by the "lost-wax" method has been well known for many years. In this method the mold is formed of dental investing material in a suitable flask with the use of a wax pattern. The wax pattern is melted so that it is either vaporized or absorbed by the molding material, and then gold or other suitable metal must be forced under pressure 60 into the molding cavity, through a suitable sprue which is formed in the investing material. It has been proposed to use compressed air for forcing the molten metal 65 through the sprue into the molding cavity. However, the use of compressed air is objectionable, because the air is readily occluded by the hot metal so that such castings are porous, which is highly objectionable. It has also been proposed to utilize suction for 70 forcing the molten metal through the sprue into the cavity of the mold, but such suction was not sufficient to give the casting the required density and uniformity.

In the methods previously used, the air 80 was utilized at comparatively low temperatures for forcing the molten metal into the mold so that the molten metal was prematurely cooled which resulted in inaccurate castings.

According to my invention, I use a hot gas or hot air at a temperature of preferably 485° C.—1000° C. although I may use even higher temperatures, dependent upon the metal to be cast. This hot air or hot gas is used to force the molten metal through the sprue into the mold cavity. Instead of using the hot air or the hot gas at the full pressure which would be caused by the high temperature, I prefer to rarefy the hot air or hot gas 90 by permitting some of it to escape before utilizing it for forcing the molten metal into the mold cavity. The high temperature of the air or gas also prevents any substantial amount thereof from being taken up by the 100

hot metal, so that dense and homogeneous castings can be secured. However, if air would be heated in a closed space to the above mentioned temperature, the pressure thereof would be too high. Hence, I believe the pressure of the air which is heated to the above mentioned temperature in a closed casing, so that air is utilized which has the necessary high temperature without having too much pressure.

As shown in Fig. 1, a hollow casing 1 which may be heat insulated, is provided which has a depending neck 5, which forms a chamber for receiving the molding flask 6. This molding flask may be of any suitable type and as illustrated herein, it is provided with a side opening 10 for receiving the dental investing material which serves as the mold. The pattern 11 is made of wax and it is formed in the usual manner.

As illustrated in Fig. 3, the pattern 11 is utilized for making a dental casting. It is connected by means of the sprue wire 12 to a cup 14 which is supported upon the flange 19 of the flask 6. After the wax pattern 11 has been surrounded by the dental investing material, the cup-shaped member 14 and the sprue wire 12 are removed, so that the top of the investing material located in the molding flask 6, has a recess which communicates with the pattern 11 by means of a sprue opening corresponding to the wire 12. When the wire 12 has been removed and the wax pattern 11 has been melted or driven off as previously mentioned, molten metal can be placed in the top recess of the dental investing material, and this can be forced into the cavity corresponding to the wax pattern 11, through the sprue corresponding to the wire 12.

The molding flask 6 preferably rests upon a perforated stand 7 and the bottom of the neck member 5 is preferably provided with perforations 8 which communicates with a tube 9 leading to the atmosphere.

The casing 1 is provided with a core 3 made of suitable insulating material upon which an electric heating coil 2 is wound. The core 3 is held in position by means of a cap 4. A jack 4a is utilized for connecting the heating coil 2 to any suitable source of electric current. By means of this heating coil 2, the air within the casing 1 can be heated to any desired temperature.

A tube 26 is connected to the casing 1. This tube 26 is provided with a dual gauge 18 which indicates both pressure and temperature, being provided with two scales for this purpose. The tube 26 is provided with a relief opening 16, controlled by a valve 17 so that some of the air within the casing 1 can be permitted to escape when the same is heated until the air in the casing 1 is at a temperature preferably not less than 500° C., and has a pressure of preferably not more than 5-20 pounds per square inch. The cas-

ing 1 is a source of heated gas under pressure, and this gas is used in casting or molding operation. The pressure of the air or gas employed depends upon the size of the casting and it is preferably one pound per penny-weight if gold is being cast. It is to be understood that the pressures above mentioned are in excess of the atmospheric pressure. Heretofore, in a device of this type, it was necessary to install an expensive pyrometer

70

if the operator wished to accurately determine the working conditions. However, according to my invention, it is merely necessary to provide a relatively inexpensive thermometer and a relatively inexpensive pressure gauge as the heating of the air in the casing is sufficient to operate both the thermometer and the pressure gauge. The thermometer may be of any suitable mechanical type. If desired, the gauge 18 may consist

75

solely of a simple pressure gauge, the reading of which can give the temperature, by means of an ordinary conversion table. The temperature of the air or gas depends on the metal or alloy which is being cast, a higher temperature being used with metals of high melting point. The temperature of the gas or air is preferably the same as or sufficiently close to the melting point, to secure a perfect casting.

80

The tube 26 is provided with a sleeve 22 which is upwardly urged by a compression spring 25. The sleeve 22 is provided with an opening which communicates with the bore of a lateral extension 21' of the hollow head 20. When the sleeve 22 has been forced to the lower or operative position in Fig. 1, against the force of the compression spring 25, the interior of the head or cap 20 communicates with the interior of the pipe 26.

90

However, when the sleeve 22 is in its upper position, then air can escape from the casing 1 and the tube 26, only through the relief opening 16. The sleeve 22 is adjacent the operating head 29 which has a quick internal thread, cooperating with the corresponding external thread 27 at the top of the tube 26. The operating head 29 is provided with a handle 24, and with a pin 23 downwardly urged by the compression spring 27 to releasably enter a corresponding recess in the top of the sleeve 22. The sleeve 22 can turn upon the tube 26 so that the hollow cap 20 can occupy the positions indicated in Fig. 2, at "B", "C" and "A". In the position indicated by "B" in Fig. 2, the handle 24 is held by the spring latch 32. The head 29 is connected to a torsion spring 28 whose upper end is suitably connected to the top of the tube 26, so that said torsion spring 28 tends to turn the handle 24 in the counterclockwise direction, to the position "A". A stop 40 is provided to prevent the head or cap 20 from moving to the left of the position "B", and a second stop 33 is provided to prevent the head

105

110

115

120

125

130

20 from moving beyond the position thereof indicated at "C". When the handle 24 moves beyond the position "C" to the position "A", the sleeve 22 is not turned any further because the pin 23 moves out of the corresponding recess therefor. When the handle 24 is moved from the position "A" to the position "C", its projection 30 contacts with the cap 20 so that the cap 20 and the handle 24 are simultaneously moved to the position "B".

10 The operation of the device is as follows: The handle 24 is held in the position "B". The thread 27 is a left hand thread so that in this position the head 29 and the sleeve 15 22 are above the operative position shown in Fig. 1. Hence, the bore of the lateral extension 21' does not communicate with the corresponding hole in the pipe 26 so that no air can escape save through the relief opening 16. The hole in pipe 26 can be provided with a valve to prevent leakage, this valve being automatically opened when the parts are in the operative position shown in Fig. 20 1. The air within the casing is heated to a suitable temperature, preferably not less than 485°-500° C., and the valve 17 is then opened to permit enough hot air to escape until the pressure indicated on the gauge 18 is about 5-20 pounds per square inch above 25 the atmospheric pressure, or even higher, depending on the metal utilized. It is a very important and novel feature of my invention to use a hot gas in the molding operation, the pressure of said gas being less than the normal pressure corresponding to the temperature of said gas. In order to secure a gas having such characteristics, I have shown a 30 source of heated gas comprising a casing having a heating element therein, and also having a relief valve, said casing being connected 35 to the molding flask by valve connected means. However, I do not wish to be limited to this specific device for producing a gas having said characteristics. The operator then places a lump of gold or other suitable metal in the top depression of the investing material, and he melts the same by an ordinary blow-pipe, or the like. The 40 sprue opening is too narrow to permit the molten metal to pass into the cavity corresponding to the pattern 11. The operator then pushes the handle 24 to the right, until it is released from the spring latch 32. The torsion spring 28 then quickly turns the head 29 until it occupies the position "C". At this point, the head 20 has descended until the asbestos gasket 21 thereof contacts with the tapered top 19 of the molding flask 6, thus starting to make an air-tight closure. The 45 torsion spring 28 then continues to turn the handle 24 and the head 29, into the position "A". As the head 29 and the handle 24 pass beyond the position "C", the head 22 no longer rotates so that the further turning 50 of the head 29, which is permitted by the

release of the pin 23 from the head 20, merely serves to downwardly force the sleeve 22 so as to further compress the asbestos gasket 21 and prevent any leakage of air. Of course, the valve 17 has been closed as soon as the 70 hot air has had the desired loss of pressure so that the hot air within the casing rushes through the bore of the lateral extension 21', and passes through the fine holes in the member 31. The hot air forces the molten metal located in the recess at the top of the investing material through the sprue opening and into the cavity corresponding to the wax pattern 11. Any excess of hot air can escape through the perforated stand 7 and the openings 8.

80 When the casting has been completed, it is merely necessary to turn the handle 24 to the position "B", whereupon the molding flask can be readily removed.

85 For convenience, the pressure of the air heated within the casing 1, before any of the said air is allowed to escape through the opening 16, may be designated as the normal pressure corresponding to said temperature. 90 However, in certain aspects of my invention, I do not wish to be limited to the use of air which is heated within a closed casing.

95 If an inert gas, such as carbon dioxide and nitrogen is to be used, then the casing and accessory parts can be filled with such inert gas before the process is started. Likewise, I may use a gas which has a reducing action at the temperatures employed. The heating coil may be made of any suitable material, 100 such as nichrome, or platinum which can withstand the high temperature. The flask which contains the investing material and which has the opening 10 can have a door to close the same.

105 While I have shown a preferred embodiment of my invention, it is clear that numerous changes and omissions could be made without departing from the spirit thereof.

I claim:

110 1. A dental casting apparatus, comprising a casing adapted to form a fluid compression chamber, a flask retaining member extending into the casing and having its lower end connected with the outside of the casing by a fluid conducting means; heating means within the casing to heat the mold and the fluid in the compression chamber, a hollow head rotatably mounted on the casing to seal the top of the flask, and means connected with the hollow head and the pressure chamber to conduct heated compressed fluid to the upper end of the flask.

115 2. A dental casting apparatus, comprising a casing adapted to form a fluid compression chamber, a tubular member extending into the casing adapted to receive a flask, a conduit connected with the lower end of the tubular member and passing through the wall of the casing, heating means within the casing 120 125 130

- to heat a fluid in the compression chamber and the mold, a hollow head rotatably mounted on the casing and adapted to seal the top of the mold, conduit means connected with the casing and the hollow head to conduct heated compressed fluid to the upper end of the flask, and means on the conduit means to reduce the fluid pressure in the compression chamber.
- 10 3. A dental casting apparatus comprising a casing adapted to form a fluid compression chamber, a flask retaining member extending into the casing and having its lower end connected with the outside of the casing by a fluid conducting means, heating means within the casing and surrounding the flask retaining member, a bored tubular member externally threaded intermediate its ends supported in the casing and connected with the compression chamber, an opening in the tubular member intermediate its lower end and the threaded portion, a sleeve slidably and turnably mounted on the lower end of the tubular member, a lateral extension on the sleeve having a bore therein and adapted to communicate with the opening in the tubular member, a hollow head attached to the lateral extension and adapted to seal the top of the mold, a compression spring interposed between the sleeve and casing, an internally threaded head, provided with a handle turnably mounted on the threaded portion of the tubular member adjacent the sleeve, a spring pressed pin in the said head adapted to enter a recess in the top of the sleeve, a torsion spring mounted on the head and tubular member, and adapted to turn the head and sleeve to bring the hollow head into operative position, whereby heated compressed fluid may pass
- 20 through the tubular member, sleeve, lateral extension and hollow head to the upper portion of the mold, a gauge on the upper end of the tubular member adapted to register the temperature and pressure of the fluid in the compression chamber, and a relief valve connected with the said chamber for regulating the fluid pressure.
- 40 4. A dental casting apparatus, comprising a casing adapted to form a fluid compression chamber, a flask retaining member extending to the casing and connected to the outside of the casing by a fluid conducting means, heating means within the casing to heat the mold and the fluid in the compression chamber, a head movably mounted on the casing to seal the adjacent end of the flask, and means connected with the head and the compression chamber to conduct heated fluid under pressure to the flask, and means to reduce the fluid pressure in the compression chamber.
- 50 53 63

In testimony whereof I affix my signature.
MAX S. SHAPIRO.
